UNITED STATES PATENT OFFICE.

HENRY HARTT, OF CHICAGO, ILLINOIS.

PRINTING-PRESS.

SPECIFICATION forming part of Letters Patent No. 662,934, dated December 4, 1900.

Application filed December 23, 1899. Serial No. 741,387. (No model.)

To all whom it may concern:

Be it known that I, HENRY HARTT, a citizen of the United States of America, and a resident of Chicago, county of Cook, State of Illinois, have invented certain new and useful Improvements in Printing-Presses, of which the following is a specification.

My invention relates to printing-presses, and has for its object an improvement in arrangement of devices for making the longitudinal folds in webs where two or more webs are united and folded together.

Presses for many-paged papers are now ordinarily made so as to combine a number of presses in one machine. Each of these presses prints upon one web of paper, and the different webs are assembled in proper order as they pass from the printing-rolls. The assembled and superimposed webs then pass over a former which gives them a longitudinal fold with one web inside of another. The longitudinally-folded webs then pass to the cutting-cylinders and folder in the manner which is well known.

It has been found by experience that where a series of superimposed webs pass over a former the paper cramps, wrinkles, offsets, smuts, and often tears as a result of running over the corners. It is well known, however, that a single web will pass over a former without any trouble whatever. I take advantage of this latter fact to overcome the previously-mentioned difficulty by making the longitudinal fold of each web separately and in such a manner that the webs are inserted one within the other in their proper order before they pass to the cutting-cylinders. The arrangement of parts by which this result may be accomplished on a three-tiered press is shown in the accompanying drawings, in which—

Figure 1 is a plan of such a press. Fig. 2 is a side elevation, one side frame being removed. Fig. 3 is an elevation of the delivery end of the press, and Fig. 4 is a section on line 4-4 of Fig. 2.

In the said drawings, A represents the rolls of paper, B the webs, and C the printing-cylinders for each web. For each web I provide a separate former F, and I place these formers one over another, so that a lower former is within the V shape of a web pass-

ing down from an upper former. It follows from running webs over formers so placed that the web from the lower former is inserted within the web from the upper former as the two are folded together in passing under the guide-roller R on their way to the cutting-cylinders K. It will be apparent from a consideration of the manner in which a web runs over a former and joins a web from another former that the longitudinally-folded webs are inserted one within another in the required manner and that there is a total absence of the cramping action due to running superimposed webs over a single former. It will also be apparent that any number of webs coming from corresponding presses and run over corresponding formers can, when the formers are arranged in the manner described, be regularly inserted one within another without encountering the difficulty of cramping, wrinkling, and tearing hereinbefore mentioned.

The herein-described process of folding webs and inserting them one within another is not herein claimed, but forms the subject-matter of a separate application filed by me February 9, 1900, and given serial number 4,587.

What I claim is—

1. The combination with a series of presses and common cutting-cylinders therefor, of a former for each press, said formers being disposed with their apexes in a line parallel with the initial direction of movement of webs when passing from said formers to the cutting-cylinders.

2. The combination with a press or presses adapted to deliver two or more printed webs which are required to be folded together, of devices for giving each web independently a longitudinal fold, means for causing such longitudinally-folded webs to be fully inserted one within another, and cutting-cylinders to which such longitudinally-folded and fully-inserted webs pass.

Signed by me at Chicago, Illinois, this 21st day of December, 1899.

HENRY HARTT.
